UNITED STATES PATENT OFFICE

2,672,039

PHOTOFASLH HOLDER

Morris Schwartz and William Castedello, Plainville, Conn., assignors to The Kalart Company Inc., Plainville, Conn.

Application December 1, 1951, Serial No. 259,364

14 Claims. (Cl. 67—31)

1

This invention relates to photoflash units comprising a reflector, mounting means for holding a flash bulb in front of the reflector and contact means for applying current to the primer of the bulb when it is desired to fire the latter. The source of current may be incorporated in the said unit or be disposed separately therefrom, for instance in the casing of a camera. Flash units of this type are sometimes referred to as "flash guns."

Conventional flash bulbs, as are used for flash units of the general type, above referred to, generally have a base and terminal connections similar to a standard incandescent bulb. A base and terminal connections of this type are highly uneconomical because, in contrast to incandescent bulbs, a flash bulb is used only for a fraction of a second and then discarded so that there is no real need for a strong and expensive base and long lasting elaborate terminal connections. Also, the base of a conventional flash bulb occupies sometimes almost half of the total length of the bulb. While this is of little importance with incandescent bulbs it is different with flash bulbs. A photographer who often has or wants to carry a substantial number of flash bulbs is bound to be space conscious and it is essential for him that the total size of a flash bulb is as small as possible.

The co-pending application Ser. No. 264,048, filed December 29, 1951, by the applicants herein discloses a new type of greatly simplified flash bulbs. The said new flash bulbs are in form of pellets or globules which have on the outside wall two terminal elements connected with the primer within the pellet or globule. In other words, the elaborate base of conventional flash bulbs is eliminated with bulbs according to the above mentioned application. The pellets may either be separate or arranged in strings similar to a sausage string so that the pellets can be easily separated as they are consecutively used.

One object of the present invention is to provide a flash unit of the general type, above referred to, which is specifically designed for use of flash pellets, capsules or globules as disclosed in the aforementioned application.

More specifically, the object of the present invention is to provide a flash unit which is adapted to be loaded with a plurality of the aforementioned pellets or globules and successively to feed the same into the firing position in front of the reflector.

Another object of the invention is to provide either ejecting means which automatically eject

2 a fired flash bulb in form of a pellet or globule upon moving a fresh one into the firing position or manually operable ejecting means.

Another object of the invention is to provide a flash unit including a magazine adapted to receive a plurality of the novel simplified flash bulbs, and including step-by-step operable feeder means, each one-step operation of the said feeder means causing movement of a fresh bulb into the firing position and into engagement with the contact means of the unit, and also providing for an automatic ejection of a fired bulb by the pressure of the next bulb.

As will appear from the previous description, the use of a flash unit according to the present invention and of flash bulbs according to the aforesaid co-pending application will simplify flash work, permit the taking of several flash pictures in rapid succession, greatly reduce the costs of taking flash pictures, and make it more convenient for the photographer to carry with him a substantial number of flash bulbs by reason of the reduced size of the individual bulbs and the storage capacity of the novel flash unit.

Other and further objects, features and advantages of the invention will be pointed out hereinafter and set forth in the appended claims forming part of the application.

In the accompanying drawings several now preferred embodiments of the invention are shown by way of illustration and not by way of limitation.

In the drawings:

Fig. 1 is a side view of a flash unit according to the invention.

Fig. 2 is a front view of Fig. 1.

Fig. 3 is a side view, partly in section, of a modification of a flash unit according to the invention.

Fig. 4 is a front view of Fig. 3.

Fig. 5 is a side view, partly in section of another modification of a flash unit according to the invention.

Fig. 6 is a fragmentary sectional view of Fig. 5.

Fig. 7 is a front view, partly in section, of the flash unit according to Fig. 5.

Fig. 8 is a front view of still another modification of a flash unit according to the invention.

Fig. 9 is a sectional side view of Fig. 8.

Fig. 10 is a sectional side view of still another modification of a flash unit according to the invention.

Fig. 11 is a front view, partly in section, of Fig. 10.

Fig. 12 is a perspective front view of Fig. 10.

Fig. 13 is a plan view of Fig. 10, the reflector being removed.

Fig. 14 is a side view, partly in section of still another modification of a flash unit according to the invention.

Fig. 15 is a fragmentary view of Fig. 14, showing the bulb holding and contact means of the unit in a position different from Fig. 14.

Fig. 16 is a front view of Fig. 15.

Fig. 17 is a plan view of the holding and contact means of the unit according to Figs. 14 and 15, and

Fig. 18 is a fragmentary detail view of the bulb holding means of the unit according to Figs. 14 and 15.

Referring first to Figs. 1 and 2 in detail, the flash unit or flash gun according to these figures is designed for use of flash bulbs forming a string, that is, each bulb consists of a closed pellet or globule 1 including the combustible foil or wire and the primer and provided on the outside with two contact elements 2 and 3 connected to the primer. The individual bulbs are joined by a narrow neck portion 4 which can be easily broken for the purpose of separating the bulbs after the same are fired.

The flash unit comprises a tube 5 which serves as a magazine for a plurality of bulbs 1. The magazine is shown as receiving five bulbs with one bulb in the firing position so that the total load capacity of the unit is six bulbs but it will be obvious that the unit can also be designed for any other load capacity. Tube 5 may be a metal tube or a transparent plastic tube enabling the photographer to ascertain easily the number of bulbs remaining in the magazine. The same result can of course be obtained by providing longitudinal observation slots in a metal tube or other suitable means indicating the number of bulbs in the magazine.

The bottom end of tube 5 is closed by a cap 6 which is removed for the purpose of inserting a new string of bulbs in the tube. The upper end of the tube supports a reflector 7 and also the holding and contact means for bulbs 1. These means are shown as an approximately semi-circular sleeve 8, the open side of the said sleeve facing away from the reflector. The wall of the sleeve is cut out or recessed to form two diametrically opposite ejection slots 9 and receiving notches 10 for the bulb terminals 2 and 3 as can best be seen on Fig. 1. Recess 9 is extended to form a slot 10' which is in alignment with a longitudinal groove or slot 11 extending throughout substantially the entire length of tube 5. Sleeve 8 is extended at its both side edges by flanges 12 to which are pivoted levers 13. These levers are biased by suitable spring means into the position shown in Fig. 1 in full lines and can be pivoted by a bulb 1 into the positions shown in dotted lines. The purpose of this arrangement will be more fully explained herein-after.

Sleeve 8 may be made of two metal sections separated by an insulation strip 14 so that each half of the sleeve thus formed constitutes a contact element for a bulb placed in front of the reflector. The two contact elements are connected in circuit with the terminals of a source of current. As previously mentioned, this source of current may be disposed separately from the flash unit for instance in the casing of a camera or as shown in a casing 15 secured to tube 5. The source of current may be formed, as shown, by a capacitor-battery system or by

one or more dry cell batteries. The circuit connections between the source of current and the contact elements formed by sleeve 8 are not shown in detail and should be visualized as being conventional and including the required switch means and connections for the synchronizer.

For the purpose of successively feeding six bulbs to the holding and contact means and in front of reflector 7, various suitable feeding means are employed. There is shown a bracket 20 which supports the lowermost bulb 1, a spring 29' being preferably interposed between the bracket and the said lowermost spring. Bracket 20 is extended through an axial slot in tube 5 into a housing 21 secured to the outside wall of the tube or integral therewith. For the purpose of lifting the bracket, two levers 22 and 23 are secured to bracket 20 within housing 21. These two levers are pivotally joined by means of a pivot 24 and a spring 25 braces the bent-off portion of lever 22 against the inner wall of housing 21. The two levers protrude from a longitudinal slot 26 of housing 21 thereby forming an actuating handle outside the housing. As will be apparent, the friction between the bent-off portion of lever 22 and the inner wall of housing 21, as caused by the pressure of spring 25, will hold bracket 20 in any position within tube 5 as long as the handle formed by levers 22 and 23 is released. When now the two levers are gripped and pressed toward each other, bracket 20 and with it the string of bulbs can be conveniently raised within the tube.

For the purpose of ejecting a fired bulb manually operable ejecting means are provided. These means are shown as comprising a plunger 30 slidably extended through reflector 7 by means of a bushing 31 or other suitable means. The inner end of the plunger supports a slightly curved disc 32 abutting against the respective bulb 1 and the outer end a button 33. A spring 34 serves to bias the plunger into the position shown on Fig. 1.

The operation of a flash unit or flash gun, as hereinbefore described, is as follows:

For the purpose of loading the unit, cap 6 is removed and levers 22 and 23 together with bracket 20 and spring 21 are withdrawn from slot 26 and tube 5 respectively. Then, a string of six bulbs is inserted and pushed upwardly until the uppermost bulb is in the position shown on Figs. 1 and 2 whereupon the bracket with the lifting levers and cap 6 are replaced. As will be apparent from the previous description, the uppermost bulb will force levers 13 from the full line position into the dotted positions until the wide part of the bulb has passed the levers whereupon the same return into the full line position. Notches 10 which are engaged by contact prongs or elements 2 and 3 limit the upward movement of the string of bulbs. At the same time, contact connections are established for the uppermost bulb when the contact prongs of the same arrive in notches 10.

Slots 11 which are engaged by contact prongs 2 and 3 of the bulbs serve to prevent an axial rotation of the bulbs within tube 5, thereby assuring that the bulb prongs will become lodged in notches 10. Slots 11 also permit to ascertain the number of bulbs remaining in the tube in case the material of the tube is opaque.

The flash unit is now ready for firing of the uppermost bulb. After the firing of this bulb in a conventional manner, plunger 30 of the ejec-

tor is depressed by means of button 33. As a result, the lateral pressure exerted upon the fired bulb will break off the same at its narrow neck 4. The next bulb is now moved into the firing position by pressing levers 22 and 23 together and lifting bracket 20 until prongs 2 and 3 of the next bulb are lodged in notches 10.

As will be noted, levers 13 and extension 12 of sleeve 8 form a slanted platform over which a broken off bulb will be guided away from the reflector. As soon as all the bulbs of a string are successively moved into the firing position, bracket 20 has reached its uppermost position and the flash unit must be reloaded.

The flash unit according to Figs. 3 and 4 is similar in principle to the flash unit described in connection with Figs. 1 and 2. Accordingly, the same numerals are employed to designate corresponding parts.

The lifting mechanism of the unit according to Figs. 3 and 4 is shown as comprising two shells 35 and 36 pivoted together by means of pivots 37. A spring 38 is biased to spread the two shells so that the lower edges of the same are frictionally pressed against the outside wall of tube 5. The lifting mechanism further comprises a platform 39 supporting the string of bulbs 1 and supported by a rod 40 which in turn is secured to shells 35 and 36 or the pivot thereof. As will be apparent, the frictional pressure caused by spring 38 will hold platform 39 in any desired position within tube 5, and pressure exerted upon the two shells in the direction of the arrows will permit a convenient lifting of the platform within the tube.

The contact elements of the flash unit are shown as two contact clamps 41 and 42 mounted on a preferably transparent bracket 43 secured to tube 5 by any suitable means such as rivets 44. Each of the two clamps should be visualized as being connected in circuit with the necessary switch and synchronizing means and the terminals of a source of current. In contrast to Figs. 1 and 2, the source of current for the flash unit according to Figs. 3 and 4 is separately disposed from the flash unit. For this purpose, two prongs 45 and 46 are shown which are mounted on tube 5 by means of an insulation sleeve 47. As will be apparent to any person skilled in the art, the source of current and the synchronizer can be connected by means of a connecting cord to these parts.

The flash unit according to Figs. 3 and 4 is provided with automatic ejecting means. For this purpose, a curved arm 50 is provided. This arm is shown as an extension of bracket 43 but can, of course, be also mounted in any other suitable manner. As can best be seen on Fig. 3, arm 50 extends partly over the uppermost bulb 1 when the latter is in its firing position.

Tube 5 may be made of metal, as shown, in which case the number of bulbs remaining in the tube may be observed through slot 11 or of transparent material such as a suitable plastic.

The operation of the unit according to Figs. 3 and 4 will be obvious from the previous description. It suffices to say that the uppermost bulb of the string of bulbs is moved into the position in which its contact prongs 2 and 3 engage contact clamps 41 and 42. The flash unit is now ready for use. After the firing of the uppermost bulb 1, the string of bulbs is lifted by means of shells 35 and 36. As a result, the curved portion of arm 50 now in engagement with the rising uppermost bulb will force the same sidewardly

toward the dotted position thereby breaking the bulb off at its neck 4. The next bulb can now be raised into the position in which its contact prongs are engaged by clamps 41 and 42.

5 The flash unit or holder according to Figs. 5, 6 and 7 is specifically designed for use with flash bulbs in form of individual closed pellets or globules 50, that is, pellets which are not joined by an easily breakable neck portion 4.

10 The flash unit according to Figs. 5, 6 and 7 comprises a housing in form of an oblong or elliptical drum 51 supporting the reflector 7. Drum 51 may support on its outside wall a synchronizer 52 of conventional design and a shoe

15 53 also of conventional design by means of which the flash unit can be attached to a bracket 53' secured to the casing of a camera. Drum 51 forms a magazine for a plurality of bulbs 50.

For the purpose of moving the bulbs success-

20 sively into the firing position, an endless conveyor strap 54 is guided within the drum over two rollers 55 and 56. The conveyor strap is rotated by roller 55 which for this purpose is fixedly mounted upon a shaft 57. This shaft is

25 rotatably supported by bearings 58 and 59 secured to drum 51 and supports at its end protruding from the drum a handle 60 in form of a wing nut. The conveyor strap mounts a plurality of circumferentially spaced bulb carriers in

30 form of U-shaped members 61. The bight of these members is secured to the strap and the preferably somewhat springy flanges form a pair of clamps between which a bulb is held as can best be seen on Fig. 7. The members may be

35 secured to the conveyor strap by any suitable means such as rivets 62. The rollers have preferably annular grooves 63 to provide space for rivet 62 and may have in one their side walls indentations engageable by projections 55' on the

40 respective wall of the casing for the purpose of detaining successive bulbs in the correct loading position, as will be more fully explained hereinafter. The carriers are made accessible for loading by removal of a cover 64.

45 The contact means of the flash unit are formed by a pair of preferably somewhat springy contact prongs 70 which engage the contact terminals 2 and 3 of a bulb placed in the proper position within the reflector (see Figs. 5 and 7). The contact prongs, if made sufficiently springy, will also serve as clamping means for the bulb but it may be preferable to provide additional guide and clamping means 71 which are preferably made of transparent material.

50 55 Contact prongs 70 should be visualized as being connected with the source of current for the flash unit. This source of current can again be separately disposed from the flash unit or be placed within the drum in the space circumscribed by the conveyor strap 54 as is more fully shown in connection with the embodiments of the invention described hereinafter.

60 Drum 51 is provided with an opening 73 and cover 64 with a similar opening 74. These two openings are preferably circular and have a diameter slightly wider than the maximum diameter of bulbs 50. They are disposed co-axially with the longitudinal axis of a bulb fitted between contact prongs 70 and clamps 71 and 72. Drum 51 and/or cover 64 are preferably provided with observation windows to ascertain the number of bulbs within the magazine.

65 The operation of a flash unit according to Figs. 5, 6 and 7 is as follows:

70 75 Let it be assumed that the magazine is loaded

and that it is desired to insert one bulb in the firing position within the reflector. This can be accomplished either by simply pressing a bulb into the proper position between the clamps 71, 72 and the contact prongs 70 or by pushing the bulb shown on Fig. 5 in dotted lines through openings 74 and 73 into the proper position between the clamps and the contact prongs. Let it now be assumed that the bulb in the reflector is fired and shall be replaced by a fresh bulb. Then, the operator turns handle 60 until a fresh bulb is in the position of the bulb shown in dotted lines and pushes this bulb with his finger against the fired bulb. As a result, the fired bulb is ejected and the new bulb takes its place. These operations are repeated until the magazine is empty. If desired, an opaque cover can be provided for opening 74.

Figs. 8 and 9 show an embodiment of the invention which is similar to the one described in connection with Figs. 5, 6 and 7. The flash unit according to Figs. 8 and 9 is also designed for independent bulbs 50. The unit comprises a cylindrical casing 80 which can be attached by means of a shoe 81 to a bracket 82 and which may also support a conventional synchronizer 83. A cylindrical drum 84 is mounted rotatably within the casing and can be rotated by means of a wing nut 85. The circumferential wall of the drum supports a plurality of radial pairs of preferably somewhat springy clamps 86. Each pair of clamps serves to receive therebetween a flash bulb. The magazine, thus formed within casing 80, is loaded by inserting the bulbs between the clamps 86 after removal of a cover 87. A bulb in the firing position is again held between the contact prongs 70 and clamps 71 and 72. Contact prongs 70 should be visualized as being connected in circuit with the source of current which is preferably disposed in the space 88 defined by drum 84. The source of current is shown as a battery 89 and a capacitor 90 but batteries only may, of course, also be employed as source of current. The circuit connections, being conventional, are not described and shown here in detail. Cover 87 and casing 80 are provided with aligned circular openings 91 and 92 respectively, for the purpose of pushing a bulb into the position of use and ejecting a previously fired bulb. A guiding groove or slot 93 is preferably provided to prevent an axial rotation of a bulb while being pushed from the position shown on Fig. 9 in dotted lines into the position of use. As will be apparent, the consequence of an axial rotation of a bulb would be that the contact terminals 2 and 3 of the bulb would not come into engagement with the contact prongs 70.

The operation of the flash unit according to Figs. 8 and 9 will be obvious from the description of the operation of the flash unit according to Figs. 5, 6 and 7.

The flash holder or unit according to Figs. 10 to 13 inclusive is similar to the one shown on Figs. 8 and 9. Accordingly, the same numerals are employed to designate corresponding parts. As it will be noted, casing 81 is tilted relative to the axis of reflector 7 while in Figs. 8 and 9 the casing is disposed at a right angle to the axis of the reflector.

Figs. 14 to 18 inclusive show an exemplification of the invention in which the magazine for the flash bulbs 50 is structurally combined with the reflector 7. For this purpose a casing 100 is secured to reflector 7. This casing houses a rotat-

able drum 101 which can be rotated by means of a wing nut 102 and supports on its circumference a plurality of circumferentially spaced pairs of preferably springy clamps 103 between which the bulbs 50 are held. The magazine can be loaded with bulbs after removal of a cover 104. Casing 100 is mounted upon a tubularly-shaped casing 105 which also may support a shoe 106 for attachment of the flash unit to the bracket of a camera casing and a synchronizer 107 of conventional design.

A flash bulb is held in the firing position in front of the reflector by means of two preferably springy contact clamps 110 and 111. These clamps are secured to a bearing sleeve 112 in which is pivotally supported on a shaft 113 journalled to casing 100. Clamps 110 and 111 are extended to form a bell-crank lever the short arm 114 of which is pivoted to an arm 115 which in turn is pivoted to a pin 116 slidably extended through hub 117 of wing nut 102. Arm 115 is engaged by the two prongs of a bifurcated spring 118 as can best be seen on Fig. 18. Spring 118 is fixedly secured for instance, by means of rivets, to a bracket 119 attached for instance by soldering to the curved wall of reflector 7. Pin 116 preferably ends in a button 120 to facilitate manipulation of the pin. Reflector 7 has in its wall an opening 121 to permit movement of a bulb 50 from the full line position into the right hand dotted position and vice versa.

The operation of a flash unit according to Figs. 14 to 18 inclusive is as follows:

Let it be assumed that a bulb is held by the contact clamps in the position of use as illustrated on Fig. 15. As will be noted, in this position of the clamps pin 116 is pulled out of casing 100 as far as possible. Let it further be assumed that the bulb is fired and shall be replaced by a fresh one. Then, drum 101 is rotated by means of wing nut 102 until a bulb is in registry with opening 121. Pin 116 is now pushed inwardly into the position shown on Fig. 14. As a result, the contact clamps swing from the position of Fig. 15 to the position of Fig. 14, the hereinbefore described linkage arrangement permitting such movement against the action of spring 118 which always tends to bias pin 116 into a position in which the contact clamps are in the position of Fig. 15. During the first part of the swinging movement of the contact clamps, the bulb gripped by these clamps is forced against the bulb placed in alignment with opening 121. Fig. 15 shows the intermediate position of the contact clamps in which the old bulb just abuts against the new bulb within the magazine. Consequently, the old bulb is forced out of its position between the clamps and ejected. As the downward movement of the contact clamps is continued, the same will grip the new bulb within the magazine. Fig. 14 shows the position of the clamps in which the same have gripped the new bulb. When now button 120 is released, the loaded spring 118 snaps the clamps back into the position of Fig. 15. In other words, a fresh bulb is now in the position of use.

The contact clamps should again be visualized as being connected in circuit with the batteries in casing 105 so that the flash unit is ready for use.

While the invention has been described in detail with respect to certain now preferred examples and embodiments of the invention it will be understood by those skilled in the art after understanding the invention, that various changes and

modifications may be made without departing from the spirit and scope of the invention, and it is intended, therefore, to cover all such changes and modifications in the appended claims.

What is claimed as new and desired to be secured by Letters Patent is:

1. A photoflash holder for use in connection with flash bulbs in form of closed transparent pellets made of insulation material and having on the outside two contact terminals connected with a primer in the pellet, the said holder comprising a casing forming a magazine adapted to receive therein a plurality of said bulbs, yieldable clamping means supported on the casing and arranged to grip by frictional pressure one of said bulbs in a predetermined position, contact means supported by the casing and positioned frictionally to engage the contact terminals of a bulb gripped by said clamping means, and moving means supported by the casing and moving the bulbs within the magazine one-by-one into gripping engagement with said clamping means and said contact means.

2. A holder as defined in claim 1, wherein said casing is tubularly shaped so as to receive the bulbs therein in form of a column, and wherein said moving means comprise lifting means mounted on said casing axially slideable relative thereto and engageable with the lowermost bulb forming said column for moving the column of bulbs toward the clamping means by sliding the lifting means relatively to the casing.

3. A holder as defined in claim 2, wherein said lifting means include arresting means frictionally engageable with the casing for retaining the lifting means in any selected axial position relative to the casing.

4. A photoflash holder for use in connection with a string of flash bulbs, each in form of a closed pellet having on the outside two contact terminals connected to a primer within the pellet, adjacent bulbs being joined by a neck portion, the said holder comprising a casing forming a magazine adapted to receive therein a plurality of said bulbs, yieldable clamping means supported on the casing and arranged to grip by frictional pressure one of said bulbs in a predetermined position, contact means supported by the casing and positioned frictionally to engage the contact terminals of a bulb gripped by said clamping means, moving means supported by the casing and acting upon the bulbs within the magazine for feeding the said bulbs one-by-one to said clamping means, and ejecting means engageable with a bulb gripped by said clamping means and arranged to apply a pressure to the said bulb in a direction slanted relative to the axis of its neck portion thereby causing breaking of the said neck portion.

5. A holder as defined in claim 4, wherein the said ejecting means comprise a movable member, and actuating means coacting with the said member for pressing the same against the bulb gripped by the said clamping means, thereby breaking the neck portion for separating the said bulb from the string of bulbs.

6. A holder as defined in claim 4, wherein the said ejecting means comprise a guide member stationarily mounted on the casing and arranged to tilt a bulb engaging the guide member relative to the axis of the respective neck portion thereby breaking the said neck portion, the said guide member being positioned to be engaged by a bulb for the purpose aforesaid in response to a lifting of the string of bulbs forcing the bulb gripped

by the clamping means out of the same and against a guide member.

7. A photoflash holder for use in connection with flash bulbs in form of individual closed pellets having on the outside two contact terminals connected with a primer within the pellet, the said holder comprising a casing forming a magazine adapted to receive therein a plurality of said bulbs, yieldable clamping means supported on the outside of said casing and arranged to grip by frictional pressure one of said bulbs in a predetermined position, contact means supported by the casing and positioned frictionally to engage the contact terminals of a bulb gripped by said clamping means, movable support means forming a plurality of compartments disposed within the casing, each of said compartments being adapted to receive one of said bulbs, the said casing having wall openings therethrough aligned with each other and said clamping and contact means, and moving means operatively coupled with the support means for moving the same into a position in which one of the bulbs is in registry with said aligned openings and said clamping and contact means, whereby the said bulb can be manually pushed through said holes into the position in which it is gripped by the clamping means and engaged by the contact means, thereby also ejecting a bulb previously occupying the said position.

8. A photoflash holder as defined in claim 7, wherein said movable support means comprise a rotatably mounted member, and a plurality of clamping members secured to said rotatable member.

9. A photoflash holder as defined in claim 8, wherein each of said clamping members comprises a pair of springy clamping elements for frictionally holding a bulb therebetween.

10. A photoflash holder as defined in claim 7, wherein said movable support means comprise an endless conveyor, rollers for guiding said conveyor and a plurality of clamping means secured to said conveyor spaced apart, each of said clamping means being adapted to receive and frictionally to hold one of said bulbs, and wherein said moving means comprise an actuating member disposed outside said casing and operatively coupled with one of said rollers for imparting a rotary movement to the conveyor.

11. A photoflash holder as defined in claim 7, wherein said movable support means comprise a drum rotatably mounted within the casing, and a plurality of clamping means secured to said conveyor circumferentially spaced apart, each of said clamping means being adapted to receive and frictionally to hold one of said bulbs, and wherein said moving means comprise an actuating member disposed outside the casing and operatively coupled with said drum for rotating the same for the purpose aforesaid.

12. A photoflash holder as defined in claim 7, wherein said contact means comprise a pair of springy electrically conductive prongs positioned frictionally to engage the contact terminals of a flash bulb placed therebetween, and wherein said clamping means comprise a pair of clamping elements positioned frictionally to engage a flash bulb placed therebetween, the said contact means and the said clamping means being disposed in a spatial relationship providing for sliding of a bulb between the said contact and clamping means and out of the same by displacement of the bulb in the same direction.

13. A photoflash holder for use in connection

11

with flash bulbs in form of individual closed pellets having on the outside two contact terminals connected with a primer within the pellet, the said holder comprising a casing forming a magazine therein for a plurality of said bulbs, rotatably mounted support means within the casing forming a plurality of compartments, each of said compartments being adapted to receive one of said bulbs, moving means operatively coupled with said support means for rotating successive bulbs into a predetermined position, clamping and contact means adapted frictionally to grip a bulb and to engage the contact terminals of a gripped bulb, said clamping and contact means comprising a pair of clamping arms pivotally mounted within the casing and positioned in a spatial relationship to the support means so as to grip in a first pivotal position a bulb in the said predetermined position and to hold in a second pivotal position the gripped bulb in a position suitable for firing, and actuating means operatively coupled with said pivotal arms for pivoting the same from one position into the other, movement of the pivotal arms from said second position into said first position causing a gripped bulb to abut against a bulb in the said

predetermined position, thereby effecting an ejection of the said gripped bulb.

14. A photoflash holder as defined in claim 13, wherein said actuating means for the pivotal arms comprise a rod mounted axially slidably relative to the casing and operatively coupled with said pivotal arms, displacement of the rod from one axial position into another axial position causing the aforesaid pivotal movement of the arms, and wherein spring means coacting with the pivotal arms bias the same into the position in which a gripped bulb is held in the aforesaid position for firing.

MORRIS SCHWARTZ
